UNITED STATES PATENT OFFICE

150,188

DESIGN FOR AN AIRPLANE HANGAR

Dwen R. Younger, San Francisco, Calif.

Application January 23, 1947, Serial No. 136,343

Term of patent 14 years

(Cl. D13—1)

To all whom it may concern:

Be it known that I, Dwen R. Younger, a citizen of the United States, residing at San Francisco, in the county of San Francisco and State of California, have invented a new, original, and ornamental Design for an Airplane Hangar, of which the following is a specification, reference being had to the accompanying drawing, forming part thereof, in which

Fig. 1 of the drawing is a perspective view of an airplane hangar, showing my new design, the doors on two sides being shown in open position,

Fig. 2 of the drawing is a plan view of the airplane hangar shown in Fig. 1, and

Fig. 3 is an elevational view showing one side of the airplane hangar; the hangar is symmetrical and presents the same view on all four sides when the doors are all in closed position.

I claim:

The ornamental design for an airplane hangar, substantially as shown and described.

DWEN R. YOUNGER.
